UNITED STATES PATENT OFFICE.

JOHN COLLIE, OF OREGON CITY, OREGON.

SELVAGE PROTECTOR.

Application filed May 22, 1926. Serial No. 111,026.

This invention appertains to looms and more particularly to a novel device for connection with a conventional loom for preventing the drawing in of the cloth at the selvage and for forming a perfect selvage.

The primary object of this invention is to provide a needle arranged on each side of the selvage and associated with the loom adjacent to the fell of the cloth and operable from the 10 lay beam for engaging the filling or weft threads for preventing the drawing in of these threads and for allowing the correct passage of the warp threads during the forming of the cloth.

It has heretofore been contemplated of providing a needle or fork for engaging the filling loops, but such devices have fallen short of their purpose and as far as I have been able to ascertain such devices have not been 20 commercially successful, due primarily to the fact that in actual practice a certain variation exists in the forming of the loops and such devices have not considered this variation.

It is therefore a salient feature of this invention to provide a needle movable in a horizontal plane toward and away from the warp threads and the fell of the cloth and normally in position for receiving the weft thread or 30 filling during the formation of the loop and the travel of the shuttle through the shed, the filling moving the needle toward the fell and the needle thereafter holding the loop in proper position during the beat of the reed.

A further object of the invention is the provision of novel means for operating the needle in a vertical plane by the lay beam when the reed pushes the filling thread in place, said means giving a smooth working steady action 40 eliminating the possibility of breakage and undue wear.

A further object of the invention is to provide a needle for engaging the filling loops at the selvage for forming a perfect selvage in 45 which possible damage to the reed is eliminated either by the needle or the temple, with which the same can be associated.

A further object of the invention is to provide a device for maintaining all warp 50 ends and selvage ends parallel while weaving and which will give more loom width for weaving with the same reed space.

A still further object of the invention is to provide a novel loom attachment of the above 55 character, which will be durable and efficient in use, one that will be simple and easy to

manufacture and which can be applied to a conventional temple and loom at a small cost.

With these and other objects in view, the invention consists in the novel construction, arrangement and formation of parts, as will be hereinafter more specifically described, claimed, and illustrated in the accompanying drawings, in which drawings:

Figure 1 is a fragmentary top plan view of 65 a conventional loom with the improved device applied thereto and connected with an ordinary temple,

Figure 2 is a transverse section taken on the line 2—2 of Figure 1 looking in the direction of the arrows showing an end elevation of the improved attachment in its operative position for releasing the filling loop, the needle having been raised by the lay beam,

Figure 3 is a view similar to Figure 1 showing the device in operation, the warp and filler threads being shown exaggerated to illustrate the formation of the loop by the needle,

Figure 4 is an end elevation of the attachment in its normal position,

Figure 5 is a front elevation of the attachment showing the same connected with an ordinary temple,

Figure 6 is an end elevation of the attachment looking in the opposite direction from Figure 4.

Referring in detail to the drawings, 10 designates the breast beam, 11 the temple bar, 12 the lay beam and 13 the reed of a loom of well known construction. B designates one of the temples of the loom, and C my improved attachment or selvage protector, it being understood that the loom is provided with two temples and that each temple has associated therewith one of the attachments. The warp threads are indicated by the reference character 14, while the weft threads or filling is indicated by the reference character 15. The temple piece can be of any preferred character or type well known to the trade and has not been shown in detail. As illustrated the same includes the usual toothed roll 16 for engaging the cloth mounted within the housing 17, one end of which is provided with clamping means 18 for engaging a bracket 19 adjustably mounted on the temple bar 11.

In the present instance the novel device C is connected with the outer end of the temple preferably by means of the clamping bolt 20 which extends through the clamping ear of the temple.

The improved device C which constitutes the invention comprises an inverted U-shaped supporting body or bracket 25 which can be formed from sheet material of the desired 5 gage and this bracket includes the depending parallel legs 26 and the connecting top plate 27. As shown the inner leg 26 is placed directly against the clamp 18 for engaging the bracket 19 and held in place by the bolt 20 10 heretobefore mentioned. As clearly shown in Figures 1 and 3 of the drawings the device C extends laterally from the outer end of the temple and the leg 26 at the outer end of the supporting frame or body 25 forms means for 15 supporting the loop engaging needle 28 and the operating means 29 therefor.

The needle 28 includes an arcuate shank portion 30 having at its inner end the depending inwardly directed loop engaging point 20 31. The opposite end of the arcuate shank 30 is provided with a substantially U-shaped attaching portion 32, the outer leg of which is rockably mounted in the outer end of a swinging arm 33, which forms a part of the operating 25 means 29. As shown the extreme outer end of the arm 33 is provided with a stop 34 arranged in the path of the U-shaped attaching portion 32 of the needle 28, which forms means for limiting the outward swinging 30 movement of the needle. The needle is normally held in contact with the stop by the use of a spring 35 coiled about the needle and having one end thereof attached to the arm 33 and its opposite end attached directly to the 35 needle. The inner end of the swinging arm 33 is connected to the outer leg 26 of the frame 25 by means of a suitable pivot 36 and the arm directly below the pivot is provided with an inwardly directed arcuate extension 40 37, the purpose of which will be hereinafter more fully described. It is to be noted that the arm 33 swings in a vertical plane and carries the needle therewith and that the needle itself is allowed a lateral swinging motion toward and away from the fell of the cloth as clearly shown in Figure 3 of the drawings and which will be hereinafter more specifically described.

An operating cam 38 for actuating the arm 50 33 is provided and this cam includes a rearwardly extending arcuate shoe 39 for a purpose, which will be also hereinafter more fully described. The cam at its inner end is mounted upon a suitable pivot 40 carried by 55 the outer arm 26 of the supporting frame 25 and the cam above the pivot 40 is provided with a rearwardly extending head 41 of a substantially circular formation for fitting in the extension 37, so as to allow the head 41 60 to act on said extension as well as against the lower edge of the arm 33. The lower edge of the extension 37 is provided with a V-shaped notch 37' for engaging a shoulder 38' on the cam 38 when the arm 33 is raised for 65 limiting the swinging movement thereof.

The shoe 39 on the cam operating lever 38 extends a suitable distance beyond the arm 33 and acts as a weight for normally holding the needle in a lowered position as shown in Figure 4 of the drawings. The arm and 70 needle due to the formation and association thereof with the frame also have a tendency to be normally held in a lowered position and in the path of the weft thread or filling when the shuttle goes through the shed. 75

In operation of the improved device, the same is attached to the outer end of the temples as described and the loom is operated in the ordinary manner. The hooked end 31 of the needle will engage the weft thread as 80 the shuttle goes through the shed and the needle will be swung on its vertical pivot in a horizontal plane toward the fell of the cloth holding the weft thread in place and effectively preventing the drawing in of the 85 selvage thus making a perfect edge which is desirable on steamer rugs, auto robes, and the like.

The loop is held in proper position until the forward beat of the lay beam and reed, 90 when the reed pushes the filling or weft thread in place at which time the lay beam will come in contact with the shoe 39 and the shoe will ride on the upper face of the lay beam and raise the arm 33 in a vertical plane 95 in a smooth steady action moving the needle 31 from out of the loop. Upon the return movement of the lay beam and reed the needle and the shoe will at once assume their normal positions, for engaging the thread on the next 100 stroke of the shuttle. If desired a long narrow fiber strip can be attached to the front of the lay to protect the face plate from any wear by the lifting shoe.

Particular attention is invited to the novel 105 manner of mounting the needle 28 upon the lifting arm 33 as the swinging movement of the needle obviates any variation in the formation of the selvage.

Changes in details may be made without 110 departing from the spirit or scope of this invention, but:

What I claim as new is:

1. The combination with a loom including a lay beam and a temple on each side of the 115 fabric being woven, of a selvage loop retainer associated with each temple, each loop retainer comprising a vertically swinging needle, a cam shoe for actuating the needle arranged in the path of the lay beam, and resilient means yieldably holding the needle laterally of the warp threads of the fabric being woven.

2. The combination with a loom comprising a lay beam and a temple on each side of the 125 cloth being woven, of a selvage loop retainer connected with the outer end of each temple comprising a swinging arm pivotally secured at its inner end, an arcuate section formed on the inner end of the arm below the 130

5 pivot, a lifting cam pivotally secured in advance of the swinging arm having a head disposed between the section and arm, a shoe formed on the cam arranged in the path of the lay beam, and a needle mounted for swinging movement upon the arm normally urged laterally of the warp threads of the fabric being woven.

10 3. A selvage loop retainer comprising a supporting and attaching body, a swinging arm connected with the body, a cam for raising and lowering the arm in direct contact therewith, and a needle pivotally secured to the arm for movement in a horizontal plane.

15 4. A selvage loop retainer comprising a frame including an attaching leg and a spaced parallel supporting leg, an arm rockably connected at one end to the supporting leg, an arcuate extension formed on the arm 20 extending inwardly of the pivot toward said arm, a lifting cam pivotally connected to the supporting leg in advance of and below the swinging arm, the cam including an inwardly directed substantially circular head lying between the arm and the extension, and a pendant shoe on the lifting cam arranged below the frame, and a needle carried by said arm.

25 5. A selvage loop retainer comprising a supporting body including an attaching leg and a supporting leg arranged in parallel relation to the first leg, a swinging arm pivotally connected at its inner end to the supporting leg, an arcuate extension formed on the pivoted end of the arm extending inwardly of the free end of said arm, a lifting cam pivotally connected at its inner end to the supporting leg at one side of and in a plane below the pivot point of the arm, an inwardly directed head formed on the cam disposed 30 between the arm and the extension, a pendant arcuate shoe formed on the cam arranged below the frame and pivot points of the arm and cams, a needle, a vertically disposed pivoted leg carried by the needle rockably

45 mounted in the free end of the arm, and means normally urging the needle in one direction toward said arm.

50 6. A selvage loop retainer comprising a supporting body, a lifting arm pivotally connected to the body for movement in a vertical plane, means for raising and lowering the arm, a needle including an arcuate body and a depending loop engaging portion on one end of the body, a U-shaped extension formed on the opposite end of the arcuate body having one leg rockably connected with the arm, a spring coiled about the leg having one end attached to the arm and the opposite end to the leg for normally holding the needles in 55 a predetermined direction against said arm.

60 7. A selvage loop retainer comprising a pivoted arm, a needle carried by the arm, an extension on the arm and spaced from the lower side thereof, the extension being provided with a notch, and a pivoted cam for lifting the arm and provided with a member arranged between the arm and the extension, the cam being provided with a shoulder adapted after the movement of the cam through a predetermined distance to engage 65 in said notch and limit the lifting movement of the arm.

70 8. A selvage loop retainer comprising a pivoted arm, a needle carried by the arm, an extension on the arm and spaced from the lower side thereof, the extension being provided with a notch, a pivoted cam for lifting the arm and provided with a member arranged between the arm and the extension, the cam being provided with a shoulder 75 adapted after the movement of the cam through a predetermined distance to engage in said notch and limit the lifting movement of the arm, and a shoe extending from the cam.

85

In testimony whereof I affix my signature.

JOHN COLLIE.
